(57) **CLAIM**

I claim the ornamental design for the octagon post cap, as shown and described.

DESCRIPTION

The cap has an opening that receives a end (usually a top) of a post. The cap is associated with deck posts and the bottom of the cap is intended to be used with lighting elements.

FIG. 1 is an isometric view of an octagon post cap according to the present invention;

FIG. 2 is a top view of the octagon post cap;

FIG. 3 is a bottom view of the octagon post cap; and,
FIG. 4 is a side view of the octagon post cap (the sides have generally the same appearance).
